Primary Examiner — Michael C Stout*Assistant Examiner* — Melvin L Davis(74) *Attorney, Agent, or Firm* — Foley & Lardner LLP**CLAIM**

We claim the ornamental design for a video game controller, as shown and described.

DESCRIPTION

FIG. 1 is a front-left perspective view from above of a video game controller;

FIG. 2 is a left side view thereof;

FIG. 3 is a right side view thereof;

FIG. 4 is a rear view thereof;

FIG. 5 is a front view thereof;

FIG. 6 is a top view thereof;

FIG. 7 is a bottom view thereof; and,

FIG. 8 is a rear-right perspective view from below thereof. Any portion of the article depicted in broken lines forms no part of the claimed design.
